**STATIONARY INDUCTION APPARATUS HAVING
SOUND ATTENUATING MEANS**

Lawrence R. Toothman and Arnold L. Horelick, Bridgeville, Pa., assignors to McGraw-Edison Company, Milwaukee, Wis., a corporation of Delaware

Filed Feb. 27, 1962, Ser. No. 176,082

12 Claims. (Cl. 336—100)

This invention relates to means for reducing audible sound propagated by encased vibratory force generating apparatus and more particularly to means for reducing audible sound generated by encased stationary induction apparatus.

Vibratory force generating electrical apparatus which produce audible sound are often immersed in a dielectric liquid within a metallic casing. Usually the force generator rests upon the bottom wall of the casing, and often a rigid base of longitudinal and transverse structural iron members is positioned below and affixed to the casing bottom wall to facilitate handling and to support the weight of the liquid dielectric and the electrical apparatus. The vibrations generated by the sound propagating apparatus may excite the rigid base structure to different amplitudes of vibration. The casing side walls are conventionally rigidly connected to the base structure, and the vibrations of the stiff base members may force the casing side walls into vibration and result in a high noise level.

It is well known that the magnetic core is a source of sound in an electrical transformer. Energization of the electrical windings surrounding the legs of the magnetic core results in alternating magnetization of the core, and the core laminations cyclically expand and contract due to the phenomenon of magnetostriction when magnetized and demagnetized by the current flowing in the transformer windings. The magnetic core thus acts as a source of 120 cycle vibrations and harmonics thereof. The vibrations generated by the magnetic core together with the weight of the core and coil assembly may force the rigid base structure beneath the casing bottom wall into vibration. The casing side walls are rigidly connected to the base structure and may be driven into vibration by the stiff base members and propagate audible noise. When the rigid base structure is resonant at 120 cycles or a harmonic thereof, the propagated noise level may be even more pronounced.

Electrical transformers are known wherein the core and coil are resiliently supported upon springs to mechanically decouple the source of sound from the casing, for example, the construction disclosed in the copending application of Morton M. Aronson et al., Serial No. 130,920 filed August 11, 1961, now U.S. Patent 3,125,736, and having the same assignee as this application. Although such spring suspension of the transformer core and coil assembly is effective in eliminating the direct metallic coupling between the source of sound and the casing, it has little or no influence on the coupling between the magnetic core and the casing established through the substantially incompressible liquid dielectric. The coupling through the liquid dielectric is comparable to the direct mechanical coupling in its ability to transmit vibrations and it forces a larger area of the casing bottom wall into vibration.

It is an object of the invention to provide an encased vibratory force generating apparatus supported on a rigid base structure wherein the base structure is acoustically isolated from the sound propagating source.

It is a further object of the invention to provide encased, liquid immersed, stationary induction apparatus supported on a rigid base structure wherein both the direct metal coupling and the coupling through the liquid

between the apparatus and the base structure is minimized.

Another object of the invention is to provide encased, oil-immersed, stationary induction apparatus supported on a rigid base structure wherein the direct metal coupling and the coupling through the liquid between the core and coil assembly and the base structure are reduced to a level substantially below that between the core and coil assembly and the casing side walls.

Another object of the invention is to provide encased stationary induction apparatus wherein the casing is integral with but is acoustically decoupled from the rigid base structure.

Another object of the invention is to provide encased stationary induction apparatus wherein the casing bottom wall is resiliently supported out of contact with the rigid base structure so that it can vibrate as a diaphragm and a hollow chamber is provided between the casing and the base structure wherein said casing bottom wall can vibrate as a diaphragm to attenuate vibratory energy and which encloses the resilient supporting means and seals them from the atmosphere.

A still further object of the invention is to provide encased stationary induction apparatus wherein the casing bottom wall is resiliently supported out of contact with the rigid base structure and having means for forming a hollow chamber between the casing and base structure wherein said casing bottom wall can vibrate as a diaphragm to attenuate vibratory energy and which integrally unites the casing to the base structure without appreciable acoustic coupling therebetween.

In accordance with the invention the bottom wall of the casing is made equal in thickness or thinner than the casing side walls and is resiliently supported out of direct contact with the rigid base structure so the casing bottom wall can vibrate as a panel and does not possess the stiffness necessary to force the casing side walls into vibration.

The features of this invention which are believed to be novel are set forth with particularity in the appended claims. The invention itself, however, both as to its organization and use, together with further objects and advantages thereof, may best be understood by reference to the following description taken in connection with the accompanying drawing in which FIG. 1 is a vertical section view through a preferred embodiment of the invention; FIG. 2 is a sectional view taken along line 2—2 of FIG. 1; FIG. 3 is a horizontal view taken along line 3—3 of FIG. 1; FIG. 4 is a partial sectional view through an alternative embodiment of the invention; and FIG. 5 is a partial view in perspective showing a preferred form of isolating pad means.

Referring now to FIGS. 1-3, the invention will be described with reference to an electrical power transformer having a three legged magnetic core 10 of magnetic steel laminations 11 defining three aligned vertical winding legs 12 connected by upper and lower yokes 14 and 15 respectively. Each winding leg 12 is surrounded by a cylindrical electrical winding 17. Channel iron side frame members 18 are disposed on opposite sides of and affixed by bolts 19 to the upper core yoke 14 and to the lower core yoke 15.

The magnetic core 10 and the windings 17 comprise a transformer core and coil assembly 20 contained within a metallic casing, or tank 21. A liquid dielectric such as transformer oil 22 fills the casing 21 to a level 23 above the core and coil assembly 20. A cushion of suitable dielectric gas 25 fills the casing 21 above the oil 22. The tank 21 includes a bottom wall 27 affixed to pairs of opposed side walls 28 and is hermetically sealed by a cover 29. For reasons to be discussed hereinafter, the casing bottom wall 27 is equal in thickness or thinner than the tank side walls 28, and in the preferred embodiment

the bottom wall 27 extends beyond the side walls 28 in a peripheral flange 31. Electrical connections to the windings 17 within casing 21 may be made through insulating bushings 32 mounted on and extending through the cover 29.

The core and coil assembly 20 is supported on a plurality of core feet 33, which may be inverted channel iron members, transverse to and disposed below the lower side frame members 18 and preferably affixed thereto by suitable means such as welding. The core feet 33 are symmetrically arranged relative to the center of gravity of the core and coil assembly 20 and preferably are disposed below the winding legs 12 where the weight of the core and coil assembly 20 is concentrated.

A rigid base structure 34 beneath the tank 21 comprises stiff channel iron members 36 longitudinal of the tank secured preferably by welding to stiff channel iron members 37 transverse of the longitudinal members 36. The longitudinal members 36 and transverse members 37 are preferably arranged symmetrically relative to the center of gravity of the core and coil assembly 20 and the tank 21, and in the embodiment of FIGS. 1-3 the transverse members 37 are disposed approximately in vertical alignment with the outer core legs 12 and outer core feet 33 and the longitudinal members 37 are positioned approximately below the casing side walls 28 longitudinal of the casing 21. In this embodiment a stiff top plate 39 is disposed above and rigidly affixed by welding to the crossed structural iron members 36 and 37. The top plate 39 is substantially coextensive with the casing bottom wall 27. The cross channel iron members 36 and 37 and the top plate 39 are sufficiently stiff so that the base structure 34 supports the entire weight of the transformer casing without bowing or warping.

Means are interposed between the casing bottom wall 27 and the base structure 34 for acoustically decoupling the casing bottom wall 27 from the rigid base structure. Preferably such acoustic decoupling means comprises means positioned between the casing bottom wall 27 and the base structure for resiliently supporting the bottom wall 27 out of direct contact with the base structure 34 so that the casing bottom wall 27 can vibrate as a diaphragm without the strength or ability to force the casing side walls 28 into vibration. Such acoustic decoupling may comprise isolating pads 41 of suitable resilient material such as synthetic rubber which raise the casing bottom wall 27 above and acoustically decouple it from the base structure 34. In the preferred embodiment of FIGS. 1-3 the isolating pads 41 rest upon the top plate 39 and are spaced apart horizontally and arranged symmetrically relative to the center of gravity of the core and coil assembly 20 so that the loading of all of isolating pads 41 is approximately uniform. Relatively large isolating pads 41A are positioned beneath the core feet 33 approximately in vertical alignment with the core winding legs 12 and transverse members 37 of the base structure and serve to acoustically isolate the weight of the core and coil assembly 20 and the oil 22 adjacent thereto from the base structure 34. Relatively small resilient pads 41B are positioned in spaced apart relation approximately below the pair of opposed tank side walls 28 longitudinal of the casing which support external radiator tubes 44, and the resilient pads 41B acoustically isolate from the rigid base structure 34 the weight of the remaining oil 22 and the weight of the casing 21 and the accessories such as the radiator tubes 44 mounted on the casing. The resilient isolating pads 41A and 41B are spaced apart and arranged symmetrically relative to the center of gravity of the core and coil assembly 20 and casing 21 so that the weight per unit area supported by all the resilient pads 41 is approximately uniform. Excessive loading or compression of any one of the isolating pads 41 would permit a greater magnitude of vibratory forces to be coupled to the base structure 34 at the one pad than at the remaining isolating pads. A typical isolating pad 75

41 after loading by the weight of oil-filled casing 21 is approximately one quarter inch in thickness, thus permitting the relatively thin bottom plate 27 to vibrate as a panel at the frequency of the sound propagating force. 5 Longitudinal and transverse serrations may be provided in the upper and lower surfaces respectively of the isolating pads 41 as shown in FIG. 5 to permit the material thereof to expand horizontally when compressed by the weight of the core and coil assembly and the oil-filled casing.

FIG. 4 illustrates an embodiment of the invention wherein the casing and rigid base structure are not integral and having means to releasably affix the casing 21 to the rigid base structure and to strengthen the casing bottom wall 27 during shipment and handling of the oil-filled transformer. The rigid base structure 34' does not have a top plate as in the embodiment of FIGS. 1-3 and comprises stiff channel iron members 36' longitudinal of casing 21 crossed by stiff channel iron members 37' transverse thereto and disposed in approximately vertical alignment below the core legs 12 and core feet 33. Plate members 42 and 43 disposed beneath and welded to the longitudinal and transverse structural iron channels 36' and 37' form box section members for the rigid base structure 34' of sufficient strength to withstand the forces encountered when vacuum is drawn on casing 21. Resilient isolating pads 41A and 41B are positioned between the casing bottom wall 27 and the longitudinal and transverse channel members 36' and 37' of the base structure 34' in a manner similar to that described for the preferred embodiment, and the resilient pads are spaced apart horizontally and arranged symmetrically relative to the center of gravity of the core and coil assembly so that the loading of the isolating pads is substantially uniform. 35 Means for releasably securing the casing 21 to the rigid base structure 34' and for strengthening the casing bottom wall 27 may include rigid internal metallic pads 48 welded to the interior surface of the casing bottom wall 27 and temporary bolts 49 protruding upwardly through clearance holes in the web of channel members 36' and in resilient isolating pads 41C disposed between the base structure 34' and bottom wall 27 and releasably engaged within threaded apertures in bottom wall 27 extending into the rigid internal metallic pads 48. The bolts 49 40 threadably engaging the rigid pads 48 temporarily affix the casing 21 to the rigid base structure 34' during shipment, processing, and handling of the transformer and strengthen the casing bottom wall 27 so that it can withstand the forces encountered when vacuum is drawn on the casing 21. The temporary bolts 49 are removed at the permanent installation site.

The core and coil assembly 22 is acoustically decoupled from the rigid base structure 34' principally by the isolating pads 41A whereas the weight of the oil 22 and the vibratory forces transmitted downwardly by the oil are acoustically decoupled from the rigid base structure 34' by the isolating pad means 41A, 41B and 41C.

The means for releasably securing the casing 21 to the rigid base structure 34' during shipment may also include jacking lugs 52 welded to the casing side walls 28 and positioned above portions 53 of the base structure 34 extending beyond the casing side walls. Rigid shipping pads 54 may be inserted between the casing bottom wall 27 and the rigid base structure 34' prior to handling and shipment by raising the casing 21 slightly using the jacking lugs 52. After the rigid shipping pads 54 are in position and the jacking means removed, the casing 21 may be releasably clamped to the base structure 34' by temporary bolts 55 passing upwardly through clearance apertures in the extending portions 53 of the rigid base structure 34' and releasably engaging threaded apertures in the jacking lugs 52. At the permanent installation site the oil-filled casing 21 is again raised slightly using the jacking lugs 52, and the rigid shipping pads 54, temporary bolts 55 and the jacking means are removed, thereby per-

mitting the weight of the oil-filled casing 21 and the core and coil assembly 20 contained therein to be supported on the resilient isolating pad means 41 which acoustically decouple the casing from the rigid base structure.

The present invention permits elimination of the resonant compliant tubes lining the casing bottom wall when utilized with the transformer sound reducing means disclosed in the copending application of Charles C. Honey et al., Serial No. 781,163, filed Dec. 17, 1958, now U.S. Patent 3,102,246, and having the same assignee as this application.

In the embodiment illustrated in FIGS. 1-3 a hollow chamber is provided between the casing and the rigid base structure wherein the casing bottom wall can vibrate as a panel to attenuate vibratory energy and the casing is integral with the base structure but is acoustically decoupled therefrom. Enclosure means is joined to the outer periphery of the casing bottom wall 27 for forming a hollow chamber between the casing and the rigid base structure wherein the casing bottom wall vibrates as a panel to attenuate vibratory energy, and preferably such means is sufficiently flexible so that it does not couple the casing to the base structure acoustically but is of sufficient strength to integrally unite casing and base structure. Preferably such flexible enclosure means includes the peripheral flange 31 on the casing bottom wall 27 having its outer margin 56 affixed in hermetically sealed relation to the outer margin on the top plate 39 of the rigid base structure 34. Thin metallic strips 58 may be interposed between the outer margin 56 on flange 31 and the top plate 39 around the entire periphery thereof and may be welded to the flange 31 and to the top plate 39. The metallic strips 58 provide the spacing between tank bottom wall 27 and top plate 39 required by the resilient isolating pads 41 which, in a typical transformer of the invention, are approximately one quarter (1/4) inch thick when compressed by the weight of the casing 21 containing oil 22 and core and coil assembly 20. The rigid connection between flange 31 and top plate 39 provided by the peripheral metallic strips 58 helps support the weight of the oil-filled casing 21 and integrally unites the casing 21 to the rigid base structure 34. The fluid-tight joint provided by the peripheral metal strips 58 between and welded to flange 31 and top plate 39 seal the isolating pads 41 from the atmosphere, and the bottom wall 27 together with the top plate 39 sealed thereto define a hollow chamber 60 positioned beneath the tank 21 wherein the bottom wall vibrates as a panel and which encloses the resilient supporting means 41 and aids in acoustically decoupling the rigid base structure 34 from the tank 21.

The tank bottom wall 27 is equal in thickness or thinner than the tank side walls 28 and acts in a manner analogous to a diaphragm and vibrates at an amplitude which will follow the vibrations originating in the magnetic core but does not possess sufficient rigidity and strength to force the tank side walls 28 into vibration. The flange 31 on the relatively thin bottom wall 27 is of sufficient radial length and flexibility to substantially decouple the base structure 34 acoustically from the casing side walls 28, and satisfactory acoustic decoupling between casing side walls 28 and rigid base structure 34 has been obtained in embodiments having flanges 31 extending approximately four inches beyond the casing side walls 28. The weight of the oil 22 and the vibratory forces transmitted downwardly by the oil are acoustically isolated from the rigid base structure by the flange 31 together with the isolating pads 41A and 41B. It will be appreciated that this embodiment eliminates the necessity of the internal metallic pads 48, the shipping pads 54, and the temporary bolts 49 and 55 for strengthening the casing bottom wall 27 and releasably securing the casing 21 to the rigid base structure 34 as in the embodiment of FIG. 4. The hollow chamber 60 may be filled with air or with material having a high coefficient of sound absorption, one suitable material being light density fiber glass.

In conventional stationary induction apparatus it is

necessary to firmly affix the casing bottom wall to the rigid base structure so that the casing bottom wall can withstand the forces when a vacuum is drawn on the casing. In the embodiment of FIGS. 1-3 the necessity of such means for strengthening the casing bottom wall sufficiently to withstand the forces involved when vacuum is drawn on the casing is obviated by means for equalizing the pressure on both sides of the casing bottom wall 27. Such pressure equalizing means may comprise means for maintaining the pressure in the chamber 60 approximately equal to the pressure of the gas cushion 25 above the oil 22, and preferably a metallic conduit 61 exterior of casing 21 at its lower end extends through flange 31 and is in communication with chamber 60 and at its upper end extends through a side wall 28 of casing 21 and is in communication with the gas 25. It will be appreciated that conduit 61 assures that equal pressure is maintained on both sides of bottom wall 27 when vacuum is drawn on casing 21, thus eliminating the necessity of rigidly affixing the casing bottom wall 27 to the base structure 34.

Although pressure equalizing conduit 61 is illustrated and described as registering with gas cushion 25, it will be appreciated that the invention is not so limited and comprehends other means for equalizing the pressure on both sides of bottom plate 27, for example, tubing registering with chamber 60 and connected at its other end to an expansion chamber maintained at the same pressure as the gas cushion 25.

Although the invention has been illustrated and described with spaced apart resilient isolating pads 41 interposed between bottom wall 27 and top plate 39, the improved results of the invention can also be obtained with a single sheet of resilient material such as synthetic rubber interposed between the rigid base structure 34 and the casing bottom wall when the elements of the core and coil assembly are symmetrically arranged relative to the center of gravity of the assembly and the accessories are symmetrically arranged on the casing. Further, it will be apparent that flexible enclosure means other than the peripheral flange 56 can join the top plate 39 in sealing relation to the outer margin of the casing bottom wall 27 to form a hollow chamber beneath the casing wherein the casing bottom wall 27 can vibrate as a diaphragm to attenuate vibratory energy without coupling the casing to the base structure acoustically.

While there have been shown and described particular embodiments of the invention, it will be obvious to those skilled in the art that various changes and modifications can be made therein without departing from the invention and, therefore it is intended in the appended claims to cover all such changes and modifications which fall within the true spirit and scope of the invention.

What we claim as new and desire to secure by Letters Patent of the United States is:

1. In stationary induction apparatus, in combination, a casing having a bottom wall and pairs of opposed side walls, dielectric liquid within said casing, a core and coil assembly immersed in said liquid within said casing and having a plurality of feet resting upon said bottom casing wall and arranged symmetrically relative to the center of gravity of said assembly, a rigid base structure beneath said bottom wall, a plurality of flat isolating pad means of resilient material having substantial horizontal dimensions interposed between said bottom wall and said base structure for resiliently supporting said casing out of direct contact with said base structure so that said bottom wall can vibrate as a panel under the vibratory forces originating in said core, certain of said resilient supporting means being positioned beneath said feet and others being positioned below each side wall of one pair of said opposed casing sidewalls, said resilient supporting means being spaced apart and the loading thereof resulting from the weight of said liquid-filled casing being approximately uniform.

2. In an electrical transformer, in combination, a tank having a bottom wall and side walls at least as thick as said bottom wall, dielectric liquid within said tank, a transformer core and coil assembly including a magnetic core having winding legs linked by electrical coils immersed in said liquid within said tank and supported upon said bottom wall, a rigid base structure beneath said tank bottom wall, flat isolating pad means of resilient material interposed between said tank bottom wall and said base structure for resiliently supporting said tank bottom wall above said base structure so that said bottom wall can vibrate as a panel and does not rigidly couple to said tank side walls through said base structure the vibratory forces originating in said core and transmitted downwardly by said liquid dielectric, and means releasable externally of said tank for rigidly connecting said tank to said base structure during shipping and handling of said transformer, said connecting means including rigid pads secured in sealing relation to the inner surface of said tank bottom wall and positioned above said base structure, said tank bottom wall having threaded apertures extending into said rigid pads and being accessible from the exterior of said tank, said rigid pads strengthening said bottom wall against the forces resulting from vacuum within said tank.

3. In an electrical transformer, in combination, a tank having side walls and a bottom wall, dielectric liquid within said tank, a transformer core and coil assembly immersed in said liquid within said tank and supported upon said tank bottom wall, a rigid base structure beneath said tank bottom wall having portions extending beyond said tank side walls, a plurality of flat isolating pad means of resilient material interposed between said bottom wall and said base structure for resiliently supporting said tank out of direct contact with said base structure so that said bottom wall can vibrate as a panel under the vibratory forces originating in the transformer core and transmitted downwardly by said dielectric liquid and does not rigidly transmit said vibratory forces to the side walls of said tank through said base structure, said isolating pad means being spaced apart and the loading thereof by the weight of said tank being approximately uniform, and means including jacking lugs on the side walls of said tank disposed above said extending portions of said base structure for rigidly connecting said tank to said base structure during shipment and handling of said transformer, said jacking lugs permitting raising of said tank relative to said base structure and the insertion of rigid members between said tank bottom wall and said base structure during shipment and handling of said transformer, said last-named means including releasable bolt means for securing said jacking lugs to said extending portions of said base structure.

4. In stationary induction apparatus, in combination, a casing having a bottom wall and pairs of opposed side walls, dielectric liquid within said casing, a core and coil assembly immersed in said liquid within said casing resting upon said bottom wall, said assembly including a magnetic core having a plurality of core legs, a plurality of crossed longitudinal and transverse structural iron members forming a rigid base structure and having a top plate disposed beneath said bottom wall, said longitudinal members being positioned approximately below one pair of said opposed sidewalls and said transverse members being disposed below legs of said core and arranged symmetrically relative to the center of gravity of said assembly, and a plurality of flat isolating pad means of resilient material interposed between said bottom wall and said top plate of said base structure for resiliently supporting said casing out of contact with said base structure so that said bottom wall can vibrate as a panel, certain of said isolating pad means being positioned below said core legs and others being disposed below said one pair of casing side walls and said isolating pad means being spaced apart and the loading there-

of by the weight of said liquid-filled casing being approximately uniform.

5. In an electrical transformer, in combination, a tank having pairs of opposed side walls and a bottom wall extending in a peripheral flange beyond said side walls, said bottom wall being at least as thick as said side walls, dielectric liquid within said tank, a transformer core and coil assembly including a magnetic core having a plurality of winding legs linked by electrical coils and a plurality of feet positioned symmetrically relative to the center of gravity of said assembly resting upon said tank bottom wall, a rigid base structure beneath said tank bottom wall including a top plate substantially coextensive with said tank bottom wall, a plurality of flat isolating pad means of resilient material interposed between said tank bottom wall and said top plate for resiliently supporting said tank bottom wall out of contact with said top plate so that said tank bottom wall can vibrate as a panel, certain of said isolating pad means being disposed below said feet and others being disposed beneath each of one pair of said opposed tank side walls, means for connecting the outer margins on said flange and said top plate in sealing relation, said bottom wall so connected to said top plate defining a hollow chamber beneath said tank wherein said tank bottom wall can vibrate as a panel to attenuate vibratory energy and enclosing said isolating pad means and sealing them from the atmosphere, said flange extending radially beyond said side walls and substantially acoustically decoupling said tank from said rigid base structure.

6. In stationary induction apparatus, in combination, a tank having side walls and a bottom wall extending in a peripheral flange beyond said side walls, dielectric liquid within said tank, a core and coil assembly including a magnetic core linked by an electrical coil immersed in said liquid within said tank and supported upon said tank bottom wall, a rigid base structure beneath said tank bottom wall including a top plate substantially coextensive with said tank bottom wall, flat isolating pad means of resilient material interposed between said tank bottom wall and said top plate for resiliently supporting said tank bottom wall out of direct contact with said base structure so that said tank bottom wall can vibrate as a panel and does not rigidly transmit to said tank side walls the vibratory forces originating in said magnetic core and transmitted downwardly by said liquid dielectric, and means for connecting the outer margin on said flange in sealing relation to said top plate, said bottom wall and said top plate sealed thereto defining a hollow chamber beneath said tank wherein said bottom wall can vibrate as a panel to attenuate said vibratory forces and enclosing said isolating pad supporting means and sealing them from the atmosphere, said flange so connected to said top plate substantially decoupling said bottom wall acoustically from said rigid base structure.

7. In stationary induction apparatus in accordance with claim 6 including conduit means communicating with the interior of said chamber and maintaining the pressure within said chamber approximately equal to the internal pressure within said tank.

8. In an electrical transformer, in combination, a tank having side walls and a bottom wall extending in a peripheral flange beyond said side walls, dielectric liquid within said tank, a transformer core and coil assembly immersed in said liquid within said tank and supported upon said tank bottom wall, a rigid base structure having a top plate beneath said tank bottom wall, flat means of resilient material interposed between said tank bottom wall and said top plate for resiliently supporting said tank bottom wall out of contact with said base structure so that said bottom wall can vibrate as a panel and does not rigidly transmit to said base structure the vibrations originating in the transformer core and transmitted downwardly by said liquid dielectric, and means including said peripheral flange for connecting said top plate to said

tank bottom wall around the entire outer margin thereof and for substantially decoupling said tank acoustically from said base structure, said connecting means together with said top plate and said tank bottom wall defining a chamber beneath said tank wherein said bottom wall can vibrate as a panel to attenuate said vibrations and surrounding said resilient supporting means and sealing them from the atmosphere.

9. In an electrical transformer, in combination, a casing having a bottom wall and side walls at least as thick as said bottom wall and said bottom wall extending in a peripheral flange beyond said side walls, dielectric liquid within said casing, a transformer core and coil assembly immersed in said liquid dielectric within said casing and supporting on said bottom wall, a gas cushion within said casing above said liquid dielectric, a rigid base structure beneath said bottom wall including a top plate substantially coextensive with said tank bottom wall, means interposed between said bottom wall and said top plate for resiliently supporting said bottom wall out of contact with said top plate so that said bottom wall can vibrate as a panel, the outer margins of said flange and said top plate being joined in sealing relation, said bottom wall and said top plate so sealed together defining a hollow chamber beneath said casing wherein said bottom wall can vibrate as a panel to attenuate vibratory energy and enclosing said resilient supporting means and sealing them from the atmosphere, and means including a conduit communicating with the interior of said sound absorbing chamber for maintaining the pressure within said chamber approximately equal to the pressure of said gas cushion.

10. In an electrical transformer, in combination, a tank having side walls and a bottom wall extending in a peripheral flange beyond said side walls, liquid dielectric within said tank, a transformer core and coil assembly immersed in said liquid within said tank and having a plurality of feet symmetrically arranged relative to the center of gravity of said assembly resting upon said tank bottom wall, a rigid base structure beneath said tank bottom wall including a top plate substantially coextensive with said bottom wall, a plurality of flat isolating pad means of resilient material interposed beneath said bottom wall and said top plate for resiliently supporting said tank bottom wall out of contact with said base structure so that tank bottom wall can vibrate as a panel and does not rigidly couple to said tank side walls the vibratory forces originating in said core and transmitted downwardly by said liquid dielectric, certain of said isolating pad means being disposed beneath said feet, said isolating pad means being spaced apart and the loading thereof resulting from the weight of said tank being approximately uniform, the outer margin of said flange being joined in sealing relationship to said top plate, said bottom wall and said top plate joined thereto defining a hollow chamber beneath said tank wherein said bottom wall can vibrate as a panel to attenuate said vibratory forces and enclosing said isolating pad means and sealing them from the atmosphere.

11. An electrical transformer comprising, in combination, a tank having side walls and a bottom wall extending in a peripheral flange beyond said side walls, dielectric liquid within said tank, a transformer core and coil assembly immersed in said liquid within said tank and

supported upon said tank bottom wall, a rigid base structure beneath said tank bottom wall having a top plate substantially coextensive with said bottom wall, flat isolating pad means of resilient material interposed between said tank bottom wall and said base structure for resiliently supporting said bottom wall above said base structure so that said bottom wall can vibrate as a panel and does not couple to said tank side wall the vibratory forces originating in said core and transmitted downwardly by said liquid dielectric, metallic strip means interposed between said top plate and said bottom wall and welded thereto around the outer margin of said flange and joining said top plate in sealing relation to said bottom wall, said top plate so joined to said bottom wall defining a hollow chamber between said tank and said base structure wherein said bottom wall can vibrate as a panel to attenuate said vibratory forces and enclosing said isolating pad means and sealing them from the atmosphere.

12. In an electrical transformer, in combination, a tank having a bottom wall and side walls at least as thick as said bottom wall and said bottom wall extending in a peripheral flange beyond said side walls, dielectric liquid within said tank, a transformer core and coil assembly including a magnetic core linked by an electrical coil immersed in said liquid within said tank and supported upon said tank bottom wall, a rigid base structure beneath said tank bottom wall including a top plate substantially coextensive with said tank bottom wall, flat isolating pad means of resilient material interposed between said tank bottom wall and said top plate for resiliently supporting said tank bottom wall out of direct contact with said top plate so that said bottom wall can vibrate as a diaphragm, said resilient supporting means being spaced apart symmetrically relative to the center of gravity of said core and coil assembly and the loading thereof, resulting from the weight of said tank containing said core and coil assembly and said dielectric being substantially uniform, and means for connecting the outer margins on said flange and said top plate in sealing relation, said bottom wall so connected to said top plate defining a hollow chamber beneath said tank wherein said bottom wall can vibrate as a diaphragm to attenuate vibratory energy and enclosing said supporting means and sealing said means from the atmosphere, said flange extending radially beyond said tank side walls and substantially acoustically decoupling said tank from said rigid base structure.
